[57] CLAIM

The ornamental design for a bottle holder, as shown and described.

DESCRIPTION

FIG. 1 is a front perspective view of a bottle holder showing my new design which is also a mirror image of the opposite side thereof;

FIG. 2 is a side perspective view of a first alternate embodiment of my new design which is also a mirror image of the opposite side thereof;

FIG. 3 is a front view of a third alternate embodiment of my new design which is also a mirror image of the opposite side thereof;

FIG. 4 is a side perspective view of a fourth alternate embodiment of my new design which is also a mirror image of the opposite side thereof;

FIG. 5 is a front view of a fifth alternate embodiment of my new design which is also a mirror image of the opposite side thereof;

FIG. 6 is a front view of a sixth alternate embodiment of my new design which is also a mirror image of the opposite side thereof;

FIG. 7 is a front plan view of my new design which is a mirror image of the opposite side thereof;

FIG. 8 is a top plan view thereof;

FIG. 9 is a bottom plan view thereof; and,

FIG. 10 is a side view thereof which is a mirror image of the opposite side thereof.

Any undisclosed surface area in any figure is without ornamentation.
